WITNESS:

T. B. Cabell

INVENTOR

BY Victor J. Evans

ATTORNEY

UNITED STATES PATENT OFFICE.

THOMAS B. CABELL, OF JACKSON, MISSISSIPPI.

INCANDESCENT-ELECTRIC-LAMP FIXTURE.

Application filed May 18, 1925. Serial No. 31,174.

To all whom it may concern:

Be it known that I, THOMAS B. CABELL, a citizen of the United States, residing at Jackson, in the county of Hinds and State 5 of Mississippi, have invented new and useful Improvements in Incandescent-Electric-Lamp Fixtures, of which the following is a specification.

My present invention pertains to incandescent electric lamp fixtures embodying 10 adjustable means whereby it is feasible to employ a shade of a single size in connection with incandescent electric lamps of various sizes, an example of such fixtures being disclosed in my Letters-Patent 1,522,942, dated January 13, 1925.

The object of my present invention is the provision of a simplified construction for adjustment purposes, and one in which 20 the locking element is advantageous because of its accessibility and also because of the facility with which it may be manipulated to perform the locking function and to effect a release when adjustment is desirable.

To the attainment of the foregoing, the invention consists in the improvement as hereinafter described and definitely claimed.

In the accompanying drawings, forming 30 part of this specification:—

Figure 1 is an elevation of a complete illuminating device including the preferred embodiment of my invention.

Figure 2 is a vertical diametrical section 35 showing the fixture constituting the preferred embodiment of my invention with some parts in elevation.

Figure 3 is a cross-section taken in the plane indicated by the line 3—3 of Figure 2.

Similar numerals of reference designate corresponding parts in all of the views of the drawings.

My novel fixture comprises a body 1 of 45 porcelain or other insulating material which is hollow and is surmounted by and connected to a metallic crown 2 of general bell configuration.

In the upper end wall of the body 1 is a 50 central aperture for the reception of an interiorly threaded bushing 3, connected at 4 to the said upper end wall.

At its lower end the body 1 is adapted for 55 the attachment by screws 5 or other appropriate means of a shade or reflector 6.

My improvement also comprises an in-

teriorly threaded socket 7 to receive an incandescent electric lamp 8, and a receptacle 9 which carries said socket 7, the said receptacle 9 being provided with lugs 10 for the 60 connection of electric wires and a receptacle including an exteriorly threaded cylinder 11 disposed and turnable in the bushing 3 and therefore adjustable vertically in said bushing.

Superposed on and connected to the receptacle 9 is a plate 12, Figures 2 and 3, provided in its periphery with a notch 13. Arranged within the hollow body 1 and against the inner side of the side wall thereof is a pin 14 which by resting in the said notch 13 as shown in Figures 2 and 3, is adapted to prevent turning of the receptacle 9 and the cylinder 11 so that the same are adjustably fixed relative to the bushing 3. 70 At its upper end the pin 14 is removably led into a socket 15 in the top wall of the body 1, and at its lower end said pin 14 is provided with a reduced extremity 16. The said reduced extremity 16 is normally arranged in an aperture in a plate 17, connected at 18 to the underside or lower end of the body 1. By virtue of this construction it will be manifest that the pin will be normally maintained in the position illustrated in Figure 2 so that said pin 14 will be enabled to preclude turning of the receptacle 9 and cylinder 11. When, however, it is desired to adjust the receptacle 9 and socket 7 so as to accurately position the filament of the lamp 8 relative to the shade or reflector 6 that is employed, the plate 17 is removed, and the pin 14 lowered out of engagement with the plate 12 whereupon the receptacle 9 may be turned about its axis for 80 the vertical adjustment of said receptacle 9 together with the socket 7 and the cylinder 11. Then when the socket 7 is in the changed position desired and the notch 13 is again in the position illustrated, the pin 14 is restored to its working position and is secured in such position by the attachment of the plate 17 to the lower end of the body 1.

It will be manifest from the foregoing 100 that my improved construction is simple, inexpensive and durable, and that the plate 17 and pin 14 are readily accessible, and that but little effort is required for the removal of the pin 14, the adjustment of 110 the receptacle 9 and the replacement of the pin 14 and the plate 17.

It will also be appreciated that notwithstanding the accessibility of the plate 17 and pin 14, the said elements are so arranged as not to detract in any measure from the finished appearance of the fixture.

I have specifically described the preferred embodiment of my invention in order to impart an exact understanding of said embodiment. I do not desire, however, to be understood as confining myself to the specific structure disclosed, my invention being defined by my appended claim within the scope of which structural changes may be made without involving departure from my invention.

Having described my invention, what I claim and desire to secure by Letters-Patent, is:—

In an incandescent electric lamp fixture, 20 the combination of an insulating body hol-

low in form and having an opening in its end wall and also having a socket in the inner side of said wall, an interiorly threaded bushing connected to the body and arranged in said opening thereof, a receptacle threaded through the bushing and equipped with a lamp socket and with means for the connection of electric conductors, a plate carried by the receptacle and having a notch in its periphery, a pin 25 movably arranged in the body and against the inner side of the wall thereof and also arranged in the notch of said plate and with its end in the socket in the end wall of the body, and a plate detachably connected to the body and receiving the opposite end of the said pin.

In testimony wherof I affix my signature.

THOMAS B. CABELL.
